UNITED STATES PATENT OFFICE.

GEORGE A. SCHAEFER, OF CHICAGO, ILLINOIS, ASSIGNOR OF ONE-HALF TO FRED W. IRVING, OF CHICAGO, ILLINOIS.

INCLOSED FUSE.

1,226,017.

Specification of Letters Patent.

Patented May 15, 1917.

Application filed April 23, 1914. Serial No. 833,872.

To all whom it may concern:

Be it known that I, GEORGE A. SCHAEFER, a citizen of the United States, residing at Chicago, in the county of Cook and State 5 of Illinois, have invented certain new and useful Improvements in Inclosed Fuses, of which the following is a full, clear, concise, and exact description, reference being had to the accompanying drawings, forming a 10 part of this specification.

My invention relates to an improved construction of inclosed fuse in which the fuse link may be readily inserted between the terminals of the fuse without the use of 15 special tools. The parts are of simple construction, and the operation of assembling a new fuse link in the fuse tube between the terminals of the fuse is readily accomplished without the exercise of special skill.

20 The several drawings illustrating my invention are as follows:

Figure 1 shows in perspective the various parts of my device in its disassembled condition;

25 Fig. 2 shows in longitudinal sectional view one end of my fuse;

Fig. 3 shows an outside view of my fuse completely assembled;

30 Fig. 4 shows in a view to a somewhat smaller scale a longitudinal section similar to Fig. 2, a fuse completely assembled.

Similar numerals refer to similar parts throughout the several views.

As shown in Figs. 1 and 2, the fuse consists of a tubular shell 1, of insulating material, preferably hard fiber, threaded externally at either end and provided at either end with opposite keyways 2. The connector at each end of the fuse is composed of a pair of contact plates 3 and 4, each of which is bent at substantially right angles so that the outwardly extending part 3^a or 4^a constitutes one of the surfaces for engaging the connector with which the 35 fuse is to be used, while the other part 3^b and 4^b forms a portion of the end wall of the fuse 2. The parts 3^b and 4^b are semi-circular in form, so that they together form a disk somewhat larger than the bore of the tube 1, and somewhat smaller than the 45 outside diameter of said tube so that the 50 internally threaded sleeve 5 may pass freely over the disk thus formed to engage the threads formed on the end of the tube 1. The portions 3^b and 4^b have lateral keys 6, 55 extending from their inner surfaces to engage the keyways 2, so that the contact plates 3^a and 4^a at one end of the fuse may be held substantially in alinement with the similar contact plates at the other end of 60 said fuse. The disk portions 3^b and 4^b are provided with vent holes 7 as may be necessary for properly releasing the pressure in the tube 1, caused by the gases resulting from the blowing of a fuse link. 65

The disk portions 3^b and 4^b have their edges slightly beveled, as indicated at 7 and 8, to engage the similarly beveled inner surface 9 of the end of the sleeve 5. The end of the sleeve projects inward beyond the 70 beveled surface 9 only a sufficient distance to positively engage the disk portions 3^b and 4^b when the sleeve is screwed onto the tube sufficiently to bring the entire beveled surface 9 into engagement with the outer 75 edge of the disk portions 3^b and 4^b, which may occur when comparatively thin fuse links are used. As a result of the construction described, when it is desired to mount one of the fuse links 10 in the shell, the 80 sleeve 5 is entirely removed from one end of the shell, and the other sleeve is sufficiently loosened to release the contact plates 3^a and 4^a of the corresponding terminal. The remaining parts of the old fuse may 85 then readily be removed. Assuming that an absorbent filling material 11 of asbestos, sand, or any other desired substance has been employed, this material is then removed from the tube, and a new fuse link 90 is readily slid into place through the loosened contact plates 3^a and 4^a. These links are sufficiently long to extend from the outer end of one terminal to the outer end of the other terminal of the fuse and may 95 be preferably of uniform thickness throughout, so that they may conveniently be made from sheet fusible metal without the addition of any terminals of any kind. One or more holes 10^a are preferably provided near 100 the middle portion of the fuse link to determine the point at which the fuse link will

blow. The fuse link thus inserted between the loosened contact plates projects sufficiently beyond the other end of the tube 1, so that the other pair of contact plates may 5 be located in proper position upon either side of it, as indicated in Fig. 4, with the keys of the contact plates engaging the keyways in the tube. Before this is done, if 10 an absorbent filler is to be used it is, of course, packed in place around the fuse link. The remaining sleeve 5 is then passed over the contact plates last named and screwed onto the end of the tube 1, until the inner beveled surface of said sleeve firmly engages 15 the outer beveled edge of said contact plates. As a result of the beveled edges referred to, the contact plates are forced firmly together and also against the end of the tube 1, so that the fuse link is held securely 20 between the contact plates. The sleeve 5 at the other end of the tube is then screwed firmly into engagement with its pair of contact plates and the fuse link is similarly clamped at that end. The fuse is 25 then ready for insertion into the connectors 12 and 13, which are preferably of the jaw type, as indicated in Fig. 3. The pressure of the contact jaws of the connectors is effective in holding the contact plates of the 30 fuse firmly in engagement with the fuse link so that for all operating conditions, the fuse link is held in good electrical contact with the terminals of the fuse, in the same manner as though special clamping devices 35 for permanently attaching the fuse link to the fuse terminals were employed.

While I have in my construction, as above described, employed beveled surfaces for exerting a clamping action upon the fused link, by means of the fuse terminals it will 40 be understood that this is not necessary, although it is a preferable construction, for without these beveled surfaces the clamping plates at either end of the fuse are held securely 45 in position against the end of the fuse tube, and the pressure exerted by the jaws of the connectors holds the contact plates securely in engagement with the fuse link during its operation.

50 My improved fuse construction is equally applicable to inclosed fuses used without absorbent filling material, and similar fuses employing any desired kind of absorbent filler.

55 While I have shown my invention in the particular embodiment herein described, it will be understood that I do not limit myself to this exact construction as I may employ any equivalent thereof without departing 60 from the spirit of my invention.

What I claim is:

1. In an inclosed fuse, the combination of a tube, a pair of plates associated with one end of said tube and each having a portion 65 extending outwardly to constitute a part of

the end wall of the tube, a fuse link having its end between said contact plates, and a sleeve carried by the end of the tube for holding the contact plates in position upon either side of said fuse link, said sleeve and 70 said outwardly extending portion having co-operating beveled surfaces for exerting a clamping effect upon said fuse link.

2. In an inclosed fuse, the combination of an insulating tube, a pair of angular clamping plates at each end of said tube, co-operating keys and keyways carried by the tube and clamping plates for alining them, a flat fuse link extending through said tube and between the clamping plates at either end 75 thereof, and a threaded sleeve carried by each end of the tube for holding the corresponding clamping plates in position upon opposite sides of said fuse link, the outwardly extending portions of said clamping 80 plates being circular and beveled and engaging similar internal beveled surfaces carried by said sleeves.

3. In an inclosed fuse, the combination of an insulating tube, a closure for each end of said tube, comprising a pair of integral bent plates, each having a longitudinally extending contact portion and a laterally extending semi-circular portion, a flat fuse link extending between the longitudinal extensions of the end closures, and a threaded sleeve mounted upon each end of said tube for holding said closures securely in contact with said tube, said closures having beveled edges co-operating with similar internal beveled surfaces upon said sleeves to clamp said longitudinal extensions against said fuse link.

4. In an inclosed fuse, the combination of an insulating tube, threaded sleeves on the ends of the tube, semi-circular end closures separate from said sleeves and held in position thereby to close the ends of said tube, said end closures being of rigid metal each having a contact blade extending rigidly 100 therefrom axially of the tube, said tube having keyways and said end closures having keys co-operating therewith to prevent rotation of said end closures relatively to said tube without interfering with the seating of said end closures against the ends of the tube, and a flat fuse link extending through said tube and between said blades, whereby the insertion of said blades into connecting jaws clamps the ends of said fuse link between said blades.

5. In an inclosed fuse, the combination of an insulating tube, threaded sleeves on the ends of the tube, a pair of rigid semi-circular metal plates separate from the corresponding sleeve and held in place thereby to close each end of said tube, said plates having rigid integral blades extending outwardly in parallel relation with the axis of the tube, said tube having keyways and said plates 115 120 125 130

having keys coöperating therewith to prevent rotation of said plates relatively to said tube without interfering with the seating of said plates against the ends of the tube, and a
5 flat fuse link extending through the tube and between the blades substantially from end to end of said blades, whereby each pair of blades firmly clamps the corresponding end

of said fuse link when said blades are inserted in a connector jaw.

In witness whereof, I hereunto subscribe my name this 15 day of April, A. D. 1914.

GEORGE A. SCHAEFER.
